UNITED STATES PATENT OFFICE

HEINRICH ZODTNER, OF BERLIN-BIRKENWERDER, GERMANY, ASSIGNOR TO C. LORENZ
AKTIENGESELLSCHAFT, OF BERLIN-TEMPELHOF, GERMANY

COOLING ARRANGEMENT FOR HIGH FREQUENCY APPARATUS

Application filed January 7, 1931, Serial No. 507,190, and in Germany January 9, 1930.

This invention relates to a cooling system for a high frequency apparatus. It differs from the present systems by the employment of a rigid body of insulating material which is light in weight, convenient to handle, cheap to manufacture, and not subject to certain disadvantages of the systems now in use.

Heretofore it has been customary, in insulating the anodes of thermionic tubes, to use india rubber hose to conduct the cooling medium to and from the jackets of the tubes. This hose had to be of sufficient length that the column of the cooling medium offered sufficient attenuation to the high frequency voltage for the ends of the tube at which the cooling medium was introduced and discharged to be at ground potential. The use of india rubber hose is unsatisfactory for several reasons. After a short period of operation the hose becomes brittle, particularly close to the anode of the tube, requiring frequent replacements. Furthermore, the hose is liable to develop leaks, particularly in that portion close to the tube which becomes brittle. Since with a high frequency apparatus the circuit impedances must be close to the tube, this is a particular inconvenience as it is liable to cause damage to these circuit elements.

30 In the drawing,

Fig. 1 is an elevation of a thermionic tube having a cooling jacket, with the device of the invention connected to the cooling jacket, and

35 Fig. 2 is a cross-section of the device of the invention shown in Fig. 1.

In Fig. 1 a thermionic tube with a cooling jacket is shown connected to a body portion B made of earthenware, porcelain or similar material, in which a duct is cut for the water or other cooling medium in such a manner that the body portion or block proper forms the walls of the duct for the passage of the cooling medium. The duct D can be arranged as shown in Fig. 2 or it may be helical.

An advantage of the arrangement shown in Fig. 2 is economy in manufacturing. In the manufacture of such a device a block is first prepared which is cut in two. Half of

the duct is then cut in each block. Prior to the burning, the two halves are pressed together and burnt in this position. Supply and discharge ducts may be cut in the same block, if desired. It is particularly advantageous 55 to use porcelain or earthenware for the block as the walls of the duct may then be glazed. The duct then offers less frictional resistance to the flow of the cooling medium and less pressure is required. Also, the duct may be 60 made of smaller cross-sectional area and this, again, is advantageous since the column will have a higher resistance per unit length, and a shorter duct may be used. Furthermore, with a duct of smaller cross-sectional area 65 there will be less distributed capacity to earth along its path.

What is claimed is:

1. A device for cooling thermionic tubes comprising a block of porcelain or earthen- 70 ware, ducts cut in said block, said ducts having a glazed surface.

2. A device for cooling thermionic tubes comprising a block formed by uniting two pieces of porcelain or earthenware, a glazed 75 duct in said block, a half of said duct being formed in each of said pieces.

3. The method of manufacturing a device for cooling thermionic tubes consisting of a block of porcelain or earthenware having 80 ducts therein, which comprises cutting said block into two pieces, cutting half of said duct in each portion of said block, and re-uniting the two pieces.

In testimony whereof I affix my signature. 85
HEINRICH ZODTNER.
